AIR MOISTENER

Maxime Jolivet, West Englewood, Teaneck, N. J.

Application September 28, 1937, Serial No. 166,208

1 Claim. (Cl. 261—23)

This invention relates to fuel treating devices for internal combustion engines and has for the primary object the provision of an efficient and inexpensive device of this character which is especially adapted for moistening air and for delivering the moistened air into the fuel of an engine prior to said fuel reaching the explosive chambers to mix with said fuel so that when the latter is fired a more complete combustion will take place providing better engine performance with fuel consumption and carbon deposits reduced to a minimum.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a fuel treating device constructed in accordance with my invention.

Figure 2 is a sectional view taken on the line 2—2 of Figure 1.

Arranged one within the other and in spaced relation are cylinders 1, 2 and 3, closed at their ends by heads 4 and 5. The cylinders are suitably secured to said heads so that the spaces between said cylinders will be separated from each other. Transverse partitions 6 located in alignment with each other are secured to the walls of said cylinders substantially midway thereof for dividing the spaces between said cylinders into lower liquid chambers 7 and 8, upper air chambers 9 and 10 and a central air mixing chamber 11. The liquid chambers 7 and 8 are partly filled with a suitable liquid such as water by way of filling tubes 13 extending through the head 4 and the partitions 6. The filling tubes are normally closed by removable caps 14. Sight gauges 15 connect with the liquid chambers 7 and 8 and are arranged exteriorly of the cylinder 1 so that a person can readily determine the height of the liquid in said chambers 7 and 8. A series of air tubes 16 extend through the head 4 and partitions 6 and terminate below the normal level of the liquid adjacent the head 5 for delivering into the liquid atmospheric air which will rise upwardly through said liquid and collect moisture therefrom and pass into the air chambers 9 and 10 by way of ports 10' formed in the partitions 6. The upper ends of the air tube 17 communicates with the air chambers 9 and 10 respectively and the open lower ends thereof terminate in the central air mixing chamber 11 adjacent the head 5. The tubes 17 convey the moisture laden air which rises into the air chambers 9 and 10

through the ports 10' to the lower end of the air mixing chamber 11. Arranged in superimposed relation in the central air mixing chamber and oppositely opposed to each other are conical shaped baffles 18, the apexes of which are open and in alignment with each other. The air discharged in the lower portion of the mixing chamber 11 must pass upwardly by the baffles and thereby become thoroughly agitated. Carried by the head 4 and extending into the uppermost portion of the air chamber 11 is an air outlet pipe 19 adapted to be connected in any well known manner to an intake manifold of an internal combustion engine so that the suction in the manifold will act to draw the atmospheric air through the liquid and through the various chambers to become thoroughly moistened and agitated and to deliver the moistened air into the manifold for mixing with the fuel of the engine so that the said fuel will be caused to more thoroughly burn and thereby produce a more efficient and smoother operation to the engine with a minimum consumption of fuel and with carbon deposits reduced to a minimum.

What is claimed is:

An air moistener comprising substantially mutually independent spaced inner, outer and intermediate concentric cylinders, heads closing the ends of said cylinders, partitions in said cylinders for dividing the latter into liquid chambers and air chambers arranged above said liquid chambers, and a mixing chamber arranged within the inner cylinder extending the full length of said cylinders and opening adjacent the bottom thereof to receive the moisture laden air from the said liquid chambers, said liquid and air chambers being located in the intermediate and outer cylinders, liquid filling tubes extending through one of the heads and the partitions for directing liquid into the said intermediate and outer liquid chambers, air admitting tubes extending through said last-named head, air chambers, partitions and terminating below the normal level of the liquid of the liquid chambers and adjacent the other head, said partitions having ports to admit moistened air from the liquid chambers to the air chambers thereabove, transfer tubes connected to the intermediate and outer air chambers and located in the inner mixing chamber and terminating adjacent the lower end thereof, spaced superimposed conical-shaped baffles having openings in the apexes thereof and arranged in the mixing chamber and having the transfer tubes extending therethrough, and means for admitting suction to the upper portion of the mixing chamber and above the uppermost baffle.

MAXIME JOLIVET.
